UNITED STATES PATENT OFFICE.

WILLIAM CONNOLLY, OF SOUTH NORWALK, CONNECTICUT.

OIL-STRAINER.

SPECIFICATION forming part of Letters Patent No. 323,637, dated August 4, 1885.

Application filed October 10, 1884. (No model.)

To all whom it may concern:

Be it known that I, WILLIAM CONNOLLY, of South Norwalk, in the county of Fairfield and State of Connecticut, have invented a new and Improved Oil-Strainer, of which the following is a full, clear, and exact description.

The object of my invention is to provide a simple, inexpensive, and efficient device for straining or clarifying oil that has been used in lubricating sewing or other machines, to allow the oil to repeatedly be used without cutting the working parts of the machines, and with little or no waste of the oil. The device is especially intended for use in connection with the oil-drip pans for sewing-machines shown in Letters Patent No. 299,743, issued to me June 3, 1884; but it may be used for straining or clarifying any other oils or liquid substances.

20 The invention consists in particular constructions and combinations of parts of the strainer, all as hereinafter fully described and claimed.

Reference is to be had to the accompanying drawings, forming part of this specification, in which similar letters of reference indicate corresponding parts in all the figures.

Figure 1 is a central vertical sectional elevation of my improved strainer. Fig. 2 is a 30 plan view thereof. Fig. 3 is a transverse section taken on the line *x-x*, Fig. 1, and Fig. 4 is a plan view in section on the line *y-y*, Fig. 1.

The letter A indicates the case or outer wall or shell of the strainer, which is shown with 35 a downwardly-tapering portion, B, in the lower extremity of which is fitted the nozzle or spout C, which may be entered into the neck of a suitable vessel or can, (not shown,) into which the oil may be discharged from the 40 strainer. The case A is made open at the top to receive one or more straining-chambers, presently to be described, and the side walls of the case A B C are imperforate or liquid-tight. At the lower end of the nozzle C, I fit 45 a perforated or wire-gauze plate, e, through which the oil escapes, said plate serving also to retain in the nozzle the filtering material D, which may consist of cotton or other fibers, felt, or any other suitable substance. I prefer to extend the wall of the nozzle C, above 50 the lower end of the part B of the case, as at e', to form a chamber or pocket at b, in which

sediment may collect, and into the upper end of the nozzle I fit a ring or cap, E, which has a perforated or wire-gauze head, e, onto which the oil may drop from the upper straining-chambers. The cap E may be made as deep as desired to enlarge the sediment-pocket b, and the cap may be fitted into a nozzle, C, extending only to a point of junction at e' of the 60 nozzle with the part B of the case, as will readily be understood.

The letter F indicates an upper oil receiving and straining chamber, which is suspended from an upper rabbet or shoulder, a, of the 65 case A, and so that the outer wall of the strainer is held away from the case some little distance to leave a space, as at G, between the chamber F and the case. To prevent the oil which may slowly filter through the chamber 70 from touching the case, I make the straining-chamber F with a perforated outer side wall, f, a perforated inner wall, f', and an imperforate bottom, f'', which tapers downward to a central point or end at f''' and between the walls f f', I place a straining or filtering substance, H, of cotton, felt, or other material, through which the escaping oil passes. There may be as many of the straining-chambers F held or "nested" in the case A as the 75 capacity of the strainer or the nature of the oil or other fluid being passed through it may require. The drawings represent two such chambers F, the inner one having a fixed top flange or rim, I, by which it is supported 80 from the top of the outer one, the inner chamber F being enough smaller than the outer one to provide a space, as at J, between the two chambers, to cause the fluid to pass from the inner one to the outer one from its lower 85 extremity at f''' when the feed of oil is slow.

At K is shown a loose cap or cover plate, which is fitted over the top of the inner strainer-chamber when more than one chamber is used, and has perforations, as at k, through 95 which the oil may pass from a pipe or conduit, L, which may connect with the oil-drip pan of a sewing or other machine, or with the drip-pans of a series of such machines, to pass the drip-oil directly through the strainer, so 100 that the clarified oil may be used over and over again without injury to the machines, and with little or no waste of the oil.

On the case A, I fit the cover M, having an

edge flange, *m*, and a central opening, *m'*, over the cap-plate *K*, through which the oil may be passed into the strainer, and a plate, *N*, hinged to the cover *M*, may be turned down 5 to close the opening *m'* and exclude dust when the strainer is not receiving liquid at the top or is out of use.

The operation is as follows: The dirty oil is passed from the pipe *L* or any vessel onto the plate *K*, and through its perforations into the inner strainer, *F*, the plate *K* holding back 10 any large particles—such as threads or metal chips—while the oil falls to the bottom *f²* of the strainer, and rises to and passes through the 15 perforated or wire-gauze inner wall, *f'*, thence through the filtering substance *H* and the outer perforated wall, *f*, down which it flows and passes to the end or central point, *f⁴*, from which it drops into the outer strainer, *F*, until it fills 20 to its perforated walls, through which and the filtering or straining substance *H* it passes and flows down to the end *f³* of the outer strainer onto and level with the perforated plate 25 *e* of the cap *E*, the impact with which tends to divide the dropping oil into fine globules, the pocket *b* collecting some of the sedimentary deposits which have chanced to escape through the strainers *F* above, and in passing through the nozzle *C* the remaining sediment 30 in the oil is retained by the filtering substance *D*, and the clarified oil escapes through the perforated plate *c* in condition to be used again.

Should the supply of oil to the strainer be 35 within its easy discharging capacity, the oil will not rise much above the top edges of the imperforate bottoms *f²* of the straining-chambers *F*, as it passes through their perforated walls and the filtering substance between 40 them; but should the supply of oil be increased the oil will rise more or less in the chambers, especially the inner one. The dripping of the oil from the central point, *f⁴*, of the inner chamber *F* onto the oil contained in the bottom *f²* of the outer chamber *F* causes waves or undulations of the oil in the latter chamber toward all sides, and facilitates the passage therethrough of the oil.

Should the supply of oil be sufficient to cause 50 it to rise in the outer chamber *F* above the point *f⁴* of the inner chamber, any sediment passing from the inner chamber to the outer one will tend to settle in the bottom of the outer one, rather than to pass through its 55 perforated side walls.

If desired, the filtering material in the straining-chambers and nozzle may be graded finer, or be more closely packed at the successive places through which the oil passes to the 60 point of discharge.

The chamber *F* and cap *E* may readily be removed for renewal of the filtering substances employed in the strainer or for cleaning the strainer at any time.

For use in straining different liquids or 65 grades thereof the side walls of the chambers *F* may consist of one or more perforated or wire-gauze plates without the filtering substance *H*, the action of the imperforate bottoms *f²* of the chambers in collecting sediment, 70 while allowing the strained liquids to pass over the top edges and escape downward to a central point of discharge at the bottom, being substantially the same in any case.

The strainers are simple in construction, 75 and are not liable to get out of order, and may be made of any required size.

Having thus described my invention, what I claim as new, and desire to secure by Letters Patent, is—

1. A strainer constructed with an outer case and one or more filtering-chambers having perforated side walls and an imperforate bottom tapering downward, to discharge the strained liquid from a central point of its under surface, substantially as herein set forth. 85

2. A strainer constructed with an outer case, *A*, and one or more filtering-chambers, *F*, having double perforated side walls, *f f'*, with a filtering substance, *H*, interposed between 90 them, and said strainer having an imperforate bottom tapering downward to a central point from which the strained liquid discharges, substantially as herein set forth.

3. The straining-chamber *F*, constructed 95 with perforated side walls and an imperforate bottom tapering downward to a central point from which the liquid discharges, substantially as herein set forth.

4. A strainer constructed with a case, *A*, 100 having a discharge-nozzle, *C*, provided with a perforated bottom-plate, *c*, a filtering substance, *D*, and a cap, *E*, having a perforated top, *e*, and projecting above the inner end of the spout to form a sediment-collecting 105 pocket, *b*, substantially as herein set forth.

5. A strainer constructed with a case, *A*, having a discharge-nozzle, *C*, provided with a perforated bottom plate, *c*, and a filtering substance, *D*, covered by a cap, *E*, having a 110 perforated top, *e*, in combination with a straining-chamber held above and dropping the liquid on the cap, substantially as herein set forth.

6. A strainer constructed with a case, *A*, having one or more straining-chambers, *F*, made with perforated sides and imperforate bottoms, a cap-plate, *K*, and cover *M*, and a discharge-spout, *C*, having a perforated bottom plate, *c*, perforated top plate, *E*, the sediment-collecting pocket *b*, and the filtering substances *H D*, placed in the straining-chambers and spout, all substantially as herein set forth. 115 120
